H. B. HALVORSEN

FORGING MACHINE

Filed Sept. 29, 1925

UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

FORGING MACHINE.

Application filed September 29, 1925. Serial No. 59,346.

While this invention relates generally to forging machines, it is more particularly directed to cutter bit sharpening machines.

Cutter bits such as used in coal mining machines are made in different sizes and it is desirable to forge each of the same by a single machine. Accordingly one object of my invention is to provide improved means for supporting work pieces of different sizes and means whereby a common die may forge the same. One of the dies herein disclosed is of the grooved roller type thereby necessitating provision of means whereby the groove may always be substantially in alignment with the center of the cooperating die in order to form the different sized bits symmetrically. This die construction is in distinction to those structures which have only a flat forging roller die and hence there is no necessity for alignment between the dies. While the structure specifically disclosed herein is adapted to support work pieces of different sizes, it will be clear that bits of the same size could also be forged so that when viewed broadly from another angle, a further object of the invention is to provide in combination work piece supporting means, a die, and means whereby said supporting means and die may have a plurality of operative forging positions relative to each other.

In one specific aspect of the invention I accomplish these objects by providing improved blank supporting means which comprises a laterally movable member having a plurality of slots, each being adapted to receive a different sized bit. It will be clear that should it be desirable to increase the output of the machine, the blank supporting means herein specifically comprising the slotted member could be so arranged that a blank could be inserted in one slot while the other slot was in an operative forging relation with respect to the die. Upon completion of the forging operation of the first blank, the supporting means could be moved quickly to bring the second slot into operative relation with the die, at the same time discharging the first forged bit which would permit the insertion of a third blank in its slot, and upon completion of the forging operation upon the second blank, reverse movement of the supporting means would discharge said second bit by means such as

disclosed. The third blank is then ready to be forged and the cycle of inserting, forming, and discharging the bit can be repeated. If for any reason access to the supporting means is interfered with during the forging operation, the length of the blank supporting means or the distance between the slots therein may be increased.

In the accompanying drawings I have shown for purposes of illustration one form which my invention may assume in practice.

In these drawings,—

Fig. 1 is a side elevation of a forging machine.

Fig. 2 is a front end elevation thereof partly broken away to show details of construction.

Fig. 3 is a fragmentary longitudinal vertical section substantially on line 3—3 of Fig. 2, parts of which are shown in elevation.

Fig. 4 is a perspective of the bit supporting member.

In the illustrative embodiment of my invention I have shown a forging machine generally indicated 1 and of the type disclosed in the patent of one Harry C. Johnson, Patent No. 1,604,414, dated Oct. 26, 1926. This machine comprises generally a reciprocable crosshead 2 actuated by suitable mechanism driven from the fly wheel pulley 3. A roller forging die 4 freely rotatably mounted in a clapper box 5 is carried by a member 6 yieldably supported upon the crosshead 2. A stationary raised die 7 is disposed in the path of movement of the roller die and has its transverse configuration substantially identical to the transverse dimensions of a groove formed in the roller periphery. During forging of a bit blank 8 the face of the bit portion will be formed against the face of the stationary raised die 7 while the lateral bit surfaces will be formed by the walls of the roller groove.

The means for supporting the bit blanks and for discharging the same is generally the same as disclosed in the patent which briefly described comprises a portion 9 upon which the raised die 7 is supported, this portion being provided with a laterally extending vertically inclined face 10. A second laterally extending supporting portion 11 is spaced rearwardly of the surface 10 and is provided with an overhanging depending

tongue 12. A combined blank support and discharge member 13 has a groove 14 in which the tongue 12 is received and an inclined face 15 which rests against the inclined face 10. Slots 16 and 17 of different dimensions are formed in the member 13 thereby accommodating bits of different sizes. As disclosed in said patent during forging of a blank one of the slots will be 10 in the same plane as the roller and raised dies. Upon discharge of the blank, the member 13 will be moved laterally to a point whereby the bit will fall forward through the open side of the slots and downwardly 15 through an opening 18 onto a chute 19. The transverse portion 9 has a portion cut away to permit the forward discharge movement of the blanks from the slots in the member 13. To move the member 13 laterally an operating lever 20 is pivotally supported on the side of the forging frame and connected to the member 13 as by a rod 21.

After the size of the bit to be forged is determined upon, the member 13 will be moved 25 to bring one or the other of the grooves 16 and 17 into operative relation to the forging dies. To prevent lateral movement of the member during a forging operation, combined feeding and interlocking mechanism is provided similar to that disclosed in 30 said patent. Briefly this mechanism comprises a longitudinally movable member 24 having an inclined cam surface 25 and a gear rack 26. The member 24 is adapted to be moved into one or the other of slots 27, 28 35 formed in the member 13 as by a gear segment 29 meshing with said rack and operated by a suitable hand lever 30 which is secured to a rock shaft 31 upon which the gear 29 40 is mounted.

In operation one or the other of the slots 45 16 or 17 will be brought into operative relation with the forging dies. The feeding member 24 will then be moved forwardly into either the slot 27 or the slot 28, depending on the bit receiving slot selected, thereby preventing lateral movement of the member 13. A blank may then be inserted in the selected slot until it rests upon the inclined cam surface 25 after which reciprocation of the roller die 4 will gradually form the bit portion while longitudinal movement of the member 24 will cause upward feeding of the blank to permit completion of the forging 50 operation. Upon completion the member 24 will be moved rearwardly to permit lateral movement of the member 13 whereupon the finished bit will be discharged through the opening 18, the same operation being carried 55 through for the other blank receiving slot.

While I have in this application specifically described one form which my invention may assume in practice, it will be understood 60 that this form of the same is shown for purposes of illustration and that the invention

may be modified and embodied in various other forms without departing from its spirit or the scope of the appended claims.

What I claim as new and desire to secure by Letters Patent is:

1. A forging machine comprising a grooved forging die, means for supporting a plurality of bit blanks, and means whereby said die and means are adapted to have a plurality of operative forging positions 75 with respect to each other to effect substantially symmetrical forging of the blanks.

2. A forging machine comprising a grooved forging die, means for simultaneously supporting bit blanks of different sizes, 80 and means for effecting substantial alignment of the groove of said die and the axes of blanks supported by said supporting means to forge said blanks substantially symmetrically.

3. A forging machine comprising a grooved forging die, means for simultaneously supporting bit blanks of different sizes, and means for effecting substantial alignment of the groove of said die and the axes 90 of blanks to forge the latter substantially symmetrically, and means for discharging blanks of different sizes including a common discharge member.

4. A forging machine comprising a 95 grooved roller forging die, a cooperating raised die, and blank supporting means having portions adapted to receive a plurality of blanks, said supporting means being operable to position a selected blank 100 to be operated upon by said cooperating dies.

5. A forging machine comprising a normally stationary blank support having a plurality of blank receiving slots, a movable 105 forging die, and means for moving said support transversely of the path of die movement to bring into the path of said die a blank supported in either slot.

6. A forging machine comprising a normally stationary blank support having a a plurality of blank receiving slots, and means for moving the same laterally.

7. A forging machine comprising a 115 grooved forging die, means for simultaneously supporting different size work pieces including movable means having spaced blank engaging walls, and means for effecting movement of said movable means to selectively place said blanks in alignment with 120 said die groove.

8. A forging machine comprising a forging die, means for simultaneously supporting a plurality of different sized blanks, said supporting means being operable to feed the said blanks to forging position and to discharge the said blanks after forging is completed.

9. A forging machine comprising a movable forging die, means for simultaneously 130

supporting a plurality of blanks, said supporting means being movable to feed said blanks to forging position, and means to prevent displacement thereof during a forging operation.

10. A forging machine comprising means for simultaneously supporting a plurality of different sized blanks, means for moving said supporting means to discharge the blanks, and means including blank feeding means for preventing discharge of said blanks during a forging operation.

11. A forging machine comprising a reciprocal die, an element having slots of different sizes to receive different sized blanks, and means for moving said element laterally of the path of movement of said die to bring said slots into operative relation with said die.

20 12. A forging machine comprising a reciprocal die, an element having slots of different sizes to receive different sized

blanks, and movable laterally of the path of movement of said die to bring said slots into operative relation with said die, and 25 means for preventing lateral movement of said supporting means during forging including a plurality of slots formed therein and a longitudinally movable member insertible therein.

30 13. A forging machine comprising a reciprocal die, an element having slots of different sizes to receive different sized blanks, and movable laterally of the path of movement of said die to bring said slots 35 into operative relation with said die, means for preventing lateral movement of said supporting means including a plurality of slots formed therein and a longitudinally movable member insertible therein, and feeding 40 means for said blanks including said longitudinally movable member.

In testimony whereof I affix my signature.
HALBERT B. HALVORSEN.
